UNITED STATES PATENT OFFICE.

CHARLES E. BUELL, OF NORTH PLAINFIELD, NEW JERSEY, ASSIGNOR TO GENERAL FIRE EXTINGUISHER COMPANY, OF NEW YORK, N. Y., A CORPORATION OF NEW YORK.

COMBINED FIRE ALARM AND EXTINGUISHING SYSTEM.

No. 903,152.

Specification of Letters Patent.

Patented Nov. 3, 1908.

Application filed May 10, 1900. Serial No. 16,239.

To all whom it may concern:

Be it known that I, CHARLES E. BUELL, of North Plainfield, Somerset county, State of New Jersey, have invented Improvements in 5 a Combined Fire Alarm and Extinguishing System, of which the following is a specification.

My invention consists primarily in the combination, with a sprinkler system provided with automatic sprinklers and a main valve for said system, of a telephone circuit and means for sending an alarm signal over said telephone circuit when the main valve is moved from the position of fully open.

15 My invention further consists of means for sending an alarm signal of one character over a telephone circuit when a sprinkler opens and an alarm signal of a different character over said telephone circuit when 20 the main valve is moved from the position of fully open.

In describing my invention in detail reference will be made to the accompanying drawings, in which

25 Figure 1 shows a combined fire alarm and extinguishing system arranged according to my invention. Fig. 2 is a detail view of the switch-board at the central station.

Referring to the drawings, P represents 30 the main riser of a sprinkler system and p one of the sprinkler pipes provided with sprinklers S adapted to be opened by heat. Located between the main riser P and the main supply pipe M S is the main valve 35 mechanism V comprising the main valve v provided with the valve-stem v s and handle H and adapted to be seated so as to exclude water from the riser P and the sprinkler system. Attached to the underside of 40 the valve v and movable therewith is a rod r which extends through an opening o in the valve-casing and is provided at its free end with a small valve o v adapted to become seated so as to close the opening or vent o 45 when the main valve is in the position of fully open, and to become unseated so as to open the vent o when the main valve is moved from the position of fully open.

In a chamber that is joined to the casing 50 of the valve mechanism V is arranged a retarding device, which consists of a hinged check-valve R V adapted to be held down to close the opening or eduction port f of pipe p' when the main valve v is open and the 55 sprinkler system filled with water as shown.

The valve R V is constructed and arranged to present a larger area to the water on the side towards the sprinklers, so that when the water pressure is equal in the main supply pipe and the sprinkler system, which 60 will be the case when the main valve v is open and the sprinkler system is filled and the sprinklers sealed, said valve R V will be held seated and the opening f of pipe p' closed. Any slight changes of pressure in 65 the system will be adjusted by the flow of water through the small hole in the valve R V indicated in the drawings by the arrow.

When a sprinkler opens, or the valve v is turned from the position of fully open, 70 thereby opening the valve o v, the pressure of the sprinkler system side of valve R V is reduced, and said valve is then opened by the greater pressure on the main supply side thereof, thereby admitting a supply of water 75 into the sprinkler system and also into the pipe p' and therethrough to the water-motor M, which serves to start said motor. The motor M is connected to and drives an electric generator D which generates an 80 electric current that is sent to the switch-board S b over the lines Z Z which includes telephone apparatus T of a subscriber's station. The current that is generated by the electric generator D and sent to the switch-board S b over lines Z Z is different in character from the current ordinarily sent over 85 said line for telephone calls, being of longer duration or of greater strength, and by employing apparatus for indicating the passing 90 of such a current an alarm is produced that indicates the opening of a sprinkler or the closing of the main valve.

The handle H of valve v is provided with an insulating pin or member k to insulate 95 the spring q of circuit key S' from the handle H when the valve v is in the position of fully open as shown. When the spring q is held as shown the lines Z Z are connected through the key S' by the contact pin j so 100 that the current generated by the generator D can be sent over said lines. When, however, the handle is turned to move valve V from the position of fully open, the spring q moves off of the insulating pin k and comes 105 into contact with the handle H, thereby breaking the contact between lines Z Z and forming a circuit through the earth and over one of the lines Z to include the generator D.

The turning of handle H opens outlet o and starts the generator D, and through the ball governor-switch B g perfects the grounded circuit. A branch Z' is shown extending from one of the lines Z and connected to a terminal stop i against which the spring q is adapted to make contact when it grounds on handle H, and a circuit is established over said line Z and the earth which excludes the resistance of the telephone apparatus T, and can be employed with charged lines for producing an alarm signal by grounding the line and by varying the line resistance when the main valve is turned from the position of fully open. By the means shown a return circuit is provided for signals which is independent of the telephone lines Z Z during the use of said lines for oral communication. At the same time that orifice o is opened an alarm is given over the then grounded line Z, and is indicated upon the alarm apparatus in the grounded branch at the switch-board S b, and this signal which denotes the turning of the valve v from its position of fully open is different in character from that sent for ordinary telephone calls or to denote the opening of a sprinkler.

A hammer h is adapted to rotate with the arbor a of the motor M and to strike the gong b to give a local alarm when the motor M is in motion. A drip-pipe d can be attached to the motor for carrying off the water discharged therefrom. The generator D is a series wound dynamo, and is provided with a circuit controlling governor of well-known construction and action for delaying the development of current until the motor M develops a satisfactory speed, when the generator D is interconnected automatically to transmit current to the switch-board S b. This interconnection is accomplished by means of the switch s, switch points f' f'', and the ball governor B g for operating said switch s. Such a controlling apparatus can be used when desired to allow the generator to gain a high rate of speed before being switched into the telephone circuit.

Two pressure gages G G' are mounted on branch pipe p² and are insulated therefrom at g' and g'', respectively. The index hand of gage G is normally in contact with the stop e and is electrically connected with the line Z and with the index hand of gage G'. A wire 4 has for its terminal the stop e' on gage G', and a wire 5 leads from the generator D to and through an alarm apparatus. When pressure is admitted to pipe p² the shunt that is normally completed over the index hand of gage G, is broken and a circuit over wires 4 and 5 is completed by the contact of the index hand of gage G' with the stop e'. The circuit thus formed furnishes an alarm circuit that is distinct from that leading to the switch-board S b and can

be made use of in connection with the equipment of buildings where it is desired to give a local alarm.

A check-valve c v is shown in the riser P to prevent a back flow from the sprinkler pipes when the outlet orifice o is opened, thereby admitting of a quicker movement of valve R V when said orifice is opened.

Three lines are shown radiating from the switch-board S b, each of said lines being provided with an annunciator numbered respectively 1^a, 2^a, 3^a. A subscriber's telephone apparatus T' is shown in line 3.

The switch-board S b is shown as composed of a series of vertical and horizontal cross-bars of well-known construction with plug-holes at their intersections, adapted to receive metal plugs p by which any desired connection can be made of the radiating lines. As shown in the drawings, the wires Z Z are connected by means of said plugs p to the first horizontal cross bar so as to operate the annunciator 1^a. After said annunciator has been operated so as to attract the attention of the operator at the central station, one of said plugs p can be removed and inserted in the second horizontal cross-bar to connect the operator's telephone at the central station with wires Z Z, and by further manipulating said plugs the wires Z Z may be connected to any telephone at the central station.

The annunciators 1^a, 2^a, and 3^a are shown in detail in Fig. 2 and are provided with the usual drops d and stops E. Connected to each of the horizontal bars in said switch-board is an electric wire extending to ground g and including an alarm bell B and battery x therefor.

The circuits for the different devices are as follows:

Telephone.—The telephone circuit for the subscriber's telephone T comprises the telephone lines Z Z, the shunt through gage G, the annunciator 1^a and the horizontal and vertical cross-bars of the switch-board S b to which the lines Z Z are respectively connected, as shown in Fig. 2.

Sprinkler alarm.—The sprinkler alarm circuit comprises the telephone lines Z Z, circuit key S', switch S, generator D, and the switch board connections above recited. Said sprinkler alarm circuit is normally open at the switch S, but when a sprinkler opens the generator D automatically operates the ball governor B g to move the switch S into a position to close said circuit, and a current entirely different from the current ordinarily sent over the telephone circuit is sent over said circuit to the central station.

Valve alarm.—The valve alarm circuit comprises the valve v, valve-stem V S, handle H, terminal stop i, branch line Z', one of the wires Z, one of the vertical bars upon the switch-board S b, one of the horizontal

bars on said switch-board, and the ground wire including the bell B and battery x. As will be seen, this circuit is likewise normally open between the handle H and branch 5 Z', but upon the turning of the handle H to close valve v the circuit becomes closed and the alarm sounded on the bell B.

What I claim as my invention and desire to secure by Letters Patent is:

- 10 1. The combination, with a sprinkler system provided with automatic sprinklers and a main valve for said system, of a telephone circuit, and means for sending an alarm signal of one character over said telephone circuit when a sprinkler opens and an alarm signal of a different character over said telephone circuit when the main valve is moved from the position of fully open, substantially as described.
- 15 2. The combination, with a sprinkler system provided with automatic sprinklers and a main valve for said system, of a telephone circuit, a generator adapted to be included in said circuit, means for actuating said generator when a sprinkler opens or when the main valve is moved from the position of fully open, and means for sending an alarm signal of one character over the telephone circuit when the generator is actuated 20 by the opening of a sprinkler, and of a different character when the generator is actuated by the movement of the main valve, substantially as described.
- 25 3. The combination, with a sprinkler system provided with automatic sprinklers and a main valve for said system, of a telephone circuit, a generator adapted to be included in said circuit, means for actuating said generator when a sprinkler opens, and a branch circuit adapted to be grounded when the main valve is moved from a position of fully open, whereby a signal of one character will be sent over the telephone circuit when a sprinkler opens, and a signal of a 30 different character will be sent over the grounded circuit when the valve is moved from its open position, substantially as described.
- 35 4. The combination, with the main supply valve of a sprinkler system, of a propelled generator having connections thereto that include a retarding device that is adapted to be made operative when a sprinkler opens to admit water to a normally closed outlet 40 for making operative the said generator, connections from said generator to a line that includes apparatus for oral communication and for receiving transmitted currents of said generator, apparatus for interconnecting said line with a series of radiating lines, each of which includes telephone apparatus, and means for normally shunting said generator out of the line, substantially as described.
- 45 5. In a combined fire alarm and extin-
- guishing system, the combination of a valve mechanism for controlling the water supply of a sprinkler system that comprises a manually operated main valve, an eduction port held closed when said valve is in the position of fully open and that is adapted to be opened when the said main valve is turned from the position of open, connections from said eduction port to a propelled electro-mechanical mechanism, and a retarding device for controlling the eduction port and adapted to prevent the inlet of water thereto when slight changes of pressure take place in the sprinkler system, substantially as described. 50
6. In a combined fire alarm and extinguishing system, the combination, with a series wound dynamo, of pressure actuated means for propelling said dynamo that is connected to an automatic sprinkler system, a telephone circuit having connections to said dynamo that includes means for denoting the action of the dynamo, and a sub-circuit connecting an alarm apparatus to said dynamo, substantially as described. 55
7. In a combined fire alarm and extinguishing system, the combination, with a series wound dynamo, of pressure actuated means for propelling said dynamo that is connected to a system of automatic sprinklers, a telephone circuit having connection to said dynamo that includes means for denoting the action of the dynamo, and a sub-circuit connecting an alarm apparatus to said dynamo through a pressure controlled switch, substantially as described. 60
8. In a combined fire alarm and extinguishing system, the combination, with a system of automatic sprinklers, of a main valve mechanism comprising a retarding device and a hand manipulated valve, connections from the retarding device to a water motor, a dynamo connected to said water motor and adapted to be driven thereby, and a speed operated switch for connecting the dynamo with a telephone circuit that includes alarm receiving apparatus, substantially as described. 65
9. In a combined fire alarm and extinguishing system, the combination, with a system of automatic sprinklers, of a main valve mechanism comprising a retarding device and a hand manipulated valve, connections from the retarding device to a water motor, a dynamo connected to said water motor and adapted to be driven thereby, a speed operated switch for connecting the dynamo with a telephone circuit that includes alarm receiving apparatus, and a sub-circuit connecting another alarm apparatus with said dynamo, substantially as described. 70
10. In a combined fire alarm and extinguishing system, the combination, with a system of automatic sprinklers, of a main valve mechanism comprising a retarding de-

vice and a hand manipulated valve; connections from the retarding device to a water motor, a dynamo connected to said water motor and adapted to be driven thereby, a speed operated switch for connecting the dynamo with a telephone circuit that includes alarm receiving apparatus, a ground connecting key held normally insulated from said hand manipulated valve, and a signal apparatus connected to the circuit that includes the ground branch, substantially as described.

11. In a combined fire alarm and extinguishing system, the combination, with a system of automatic sprinklers, of a main valve mechanism comprising a retarding device and a hand manipulated valve, connections from the retarding device to a water motor, a dynamo connected to said water motor and adapted to be driven thereby, a speed operated switch for connecting the dynamo with a telephone circuit that includes alarm receiving apparatus, a sub-circuit connecting a local alarm apparatus with said dynamo, and a grounded circuit connecting the hand manipulated valve with an additional alarm apparatus, substantially as described.

12. The combination, with a sprinkler system, of a telephone circuit, a pressure controlled transmitter that is adapted to be made operative by a variation of pressure

in the pipes of said system when a sprinkler opens to transmit signals over said telephone circuit, apparatus for denoting the transmitted signals, connections from said transmitter to the main valve of said system of sprinklers that include apparatus adapted to be made operative by the turning of said valve from the position of fully open to connect the transmitter with a grounded circuit which is independent of said telephone circuit when in its normal position, and means at a remote station for denoting the signals due to the turning of said valve, substantially as described.

13. The combination, with a sprinkler system provided with a main valve, of a telephone circuit, a signal transmitter that is adapted to be made operative to transmit alarm signals over said telephone circuit when a sprinkler opens, connections from said telephone circuit to earth that include the transmitter and a movable part of the main valve of the sprinkler system, and receiving apparatus in operative relation to said grounded line for causing the turning of said valve to be denoted, substantially as described.
